UNITED STATES PATENT OFFICE.

HERBERT S. ATKINSON, OF WEEHAWKEN, NEW JERSEY, ASSIGNOR TO HAYWARD COMPANY, A CORPORATION OF NEW YORK.

BUCKET.

No. 906,184.

Specification of Letters Patent.

Patented Dec. 8, 1908.

Application filed August 21, 1907. Serial No. 389,424.

To all whom it may concern:

Be it known that I, HERBERT S. ATKINSON, a citizen of the United States, and a resident of the town of Weehawken, in the county of 5 Hudson and State of New Jersey, have invented certain new and useful Improvements in Buckets, of which the following is a description.

This invention relates to an improvement 10 in buckets such as are commonly employed for loading, unloading, dredging and similar work, and in the present instance I have shown such improvements as are embodied in a bucket of the "clam-shell" type, although it is of course to be understood that 15 such improvements are applicable to buckets of other types.

In carrying out this invention, it is my 20 purpose to provide a bucket embracing the desirable features of simplicity, durability and strength, and furthermore, to so construct and arrange various parts going to make up the entire structure, that such bucket will work easily and positively. Fur- 25 thermore, a bucket constructed as shown may be worked continuously and for long periods of time without being subjected to derangement and injury.

This invention consists in the construc- 30 tion, combination and arrangement of parts set forth in and falling within the scope of the appended claims.

Referring now to the accompanying drawings in detail, Figure 1 is a perspective view 35 of a "clam-shell" bucket provided with my improvement, such bucket being shown in open position, the operating ropes in the bucket, which are arranged in the manner well known, being omitted. Fig. 2 is a de- 40 tail view of a portion of the center wheel or power sheave of the bucket. Fig. 3 is a sec- 45 tional view taken through the sheave wheel and showing the manner of securing the operating chains thereto. Fig. 4 is a view in side elevation of the sheave wheel, showing 50 the manner of attaching the rope guard to the shaft thereof. Fig. 5 is a view in elevation of the sheave wheel showing the rope guard in connection therewith, and also illus- 55 trating a portion of the bucket and the manner of bracing the same.

Referring now to the accompanying drawings in detail, A and B indicate the sections 60 of the bucket pivotally connected together 55 by the shaft C, which may be termed the

power-wheel shaft. Each of these sections is provided, adjacent to the point where it is pivoted to the shaft, with a cross brace 1 and an angle brace 2, the angular arms 3—3 merging in a central portion at approximately the central part of the cross brace 1. These braces are intended to impart strength and rigidity to the bucket sections at the point where they are hinged to the shaft C and where they are subjected to considerable strain.

Each of the sections is provided with side lugs 5, having secured thereto one end of the side connecting bars 6, the opposite or top ends of such bars being connected by the pivot 7 passing through the bearing 8, the construction being such that the bucket sections may swing upon such pivot and be opened and closed in the well known manner.

Upon the shaft C is mounted the wheel D 75 having a hub section 9 for passage of the shaft C, the central portion of such hub being enlarged as is shown at 10.

The periphery of the wheel section 11 is circumferentially grooved, as at 12, to receive the operating rope of the bucket (not shown). The end portions of the hub 9 are also grooved or cut away at 13—13, to receive duplex sections 14—14 of the chains 15, the opposite ends of such chains being suitably connected to suspending rods 16—16. The end links 17, 17—17, 17 of the duplex portions of the chains fit into transverse bores or slots 18, 18—18, 18, while a longitudinal bore 19 extends alongside the bore or passage of the shaft C, the bore 19 being designed to receive the fastening pin 20, which passes through the links 17, such pin providing means whereby the links are fastened to the hub. It will be noted that between the links 17 of each duplex chain section the pin 20 is exposed, the grooved or cut-away portion 13 forming practically a continuation of the bore 19.

By such a construction as just described, 100 the chain section may be easily and readily connected to and disconnected from the wheel D.

In the present instance, I have shown the chains herein employed as each comprising 105 a duplex section and a single section, so constructed that when the sheave wheel has made one complete rotation, as in the closing of the bucket, the duplex section will wrap completely around the sheave on the grooved 110

ends of the hub, without such duplex section overlapping; that is to say the duplex section of each chain is just long enough to encircle the grooved end of the hub to which it is attached, and the single section 15 of each chain, as the power wheel or sheave continues to rotate in the action of closing the bucket, will wrap on the center section of such grooved hub in between the duplex section of the chain and without coming in contact with the latter section, until the bucket is closed. But I wish it to be understood that I do not limit myself to the use of a chain formed of a duplex section and a single section. In some instances, it may be desirable to employ another type of chain, and in my co-pending application Serial No. 392,988, I have shown certain types of chain which are particularly applicable to buckets of various sizes.

In Fig. 1, the construction of the bearing 8 is shown, being in form a semi-circular hood with circular end plates 8^a and provided underneath at desired intervals along its length with spacing lugs 8^b through which and the end plates passes the pivot 7. The spaces between adjacent lugs form recesses for the reception of the ends of side bars 6 and suspending rods 16 and 16. Any great lateral movement of the ends of the bars 6 and rods 16 on the pivot 7 is thus prevented.

In Fig. 1 I have shown inclined braces or strips 21 connected at their upper ends, as at 22, to the side bar 6, and at their lower ends 35 converging and being fastened, as at 23, to the central lugs 24 of the bucket sections. I provide these braces for the purpose of maintaining the chains suspended in proper alignment relative to the hub section. It 40 will be noted that, as heretofore described, the chains are connected to suspending rods 16-16, and that these rods are in turn connected to the pivot 7. By employing the braces 21 to hold the side bars 6 spaced apart, 45 and constructing the hood bearing 8, as described, the tendency of the chains 15 to be deranged by any sidewise thrust or strain upon the bearing 8 is obviated, and interference with the proper wrapping or coiling 50 of the chains is thus avoided.

In Figs. 1, 4 and 5 I have shown the wheel D as provided with a rope guard, the latter comprising the spider D', having the end wells 25 perforated to permit the passing of 55 the shaft C, and such wells are connected by means of angular guard arms 26; each of which, at a point adjacent to the periphery of the wheel has a grooved sleeve 27. It will be evident that the rope encircling the sheave 60 runs between the groove in the periphery of the sheave and the groove in the guard shoe.

I have found by experience that a bucket constructed in the manner herein described can be worked repeatedly and freely without 65 the presence of excessive friction, or the

chains becoming fouled, disengaged or disturbed. Furthermore, in the case of breaking or other accident to either the chains or the means connecting the same to the sheave, such chain may be easily removed 70 by simply withdrawing the bar 20 from the bore 19 and the broken part replaced without any considerable labor or any great loss of time. Furthermore, the parts of such bucket are readily accessible in case it 75 should be necessary to make such repairs, or to dismantle the bucket.

While I have herein shown and described my improvements as applied to a "clam-shell" type of bucket, it will of course be understood that it is applicable also to other types, and furthermore, I wish it to be understood that I do not confine myself to all the precise details of construction herein shown and described, as modification and 85 variation may be made without departing from the spirit of the invention or scope of the claims.

Having thus described my invention, what I claim is:

1. The combination of a bucket formed of a plurality of sections, mechanism for operating said sections to open and close the same, such mechanism including flexible means formed of a plurality of sections connected 95 together, one of said sections comprising a plurality of flexible members arranged approximately in parallelism and offset laterally from the other section.

2. The combination with a receptacle 100 formed of a plurality of sections, of mechanism for operating said sections to open and close the same, such mechanism including flexible means formed of connected sections, certain of said sections comprising a plurality 105 of flexible members spaced apart and arranged side by side.

3. The combination with a bucket formed of a plurality of sections, of means for operating said sections to open and close the same, 110 such means including a plurality of chains, each of said chains embracing in its construction a single section, and a duplex section connected to the single section.

4. A bucket, comprising a plurality of sections, means for pivotally connecting the sections, a power shaft, a wheel mounted thereon and operating chains for the bucket, each chain being formed of a plurality of connected sections, one of said sections being 115 linked to an adjacent connected section, so that it lies between the members forming the adjacent section when the chain is coiled or wrapped in the closing of the bucket.

5. A bucket comprising a plurality of sections, a power shaft connecting said sections, a pivot pin, means connecting said pivot pin with the bucket sections, a power wheel mounted upon the shaft, and a suspended chain formed of sections of different widths, 12

having the widest section thereof divided and secured to the power wheel and the narrower section suspended from the pivot pin.

6. A bucket comprising a plurality of sections, a pivot about which said sections move, a power shaft connecting the sections, a power wheel, and a chain for opening and closing the bucket sections, said chain comprising a single and a plural section, the single section suspended from the pivot and the plural section secured to the power wheel.

7. A bucket comprising a plurality of sections, a power shaft therefor, a power wheel for said shaft, said power wheel having longitudinal and transverse grooves cut into the hub thereof, and a plurality of depending chains, each formed of plurality of sections, said sections differing in width, and means for securing the chains at the transverse grooves in the hub said means being accessible through the longitudinal grooves.

8. A bucket comprising a plurality of sections and means for opening and closing the sections, including a power wheel having a hub, and an operating chain formed of a multiplicity of sections of different width, each section having a length substantially coextensive with the circumference of the hub.

9. The combination of a bucket formed of a plurality of sections, mechanism for operating said sections to open and close the same, such mechanism including flexible means formed of a plurality of sections arranged end

to end and offset laterally one from the other to enable one section to lie parallel with the other section when the sections are wrapped or coiled in the closing of the bucket.

10. A bucket comprising a plurality of sections, a power shaft connecting said sections, a pivot-pin, means connecting said pivot-pin with the bucket sections, a power wheel mounted upon the shaft, and a chain for opening and closing the bucket sections, said chain consisting of a single and a plural section, one of which sections is suspended from the pivot-pin and other connected to the power wheel.

11. The combination with a plurality of bucket sections, means for opening and closing the bucket sections including a power shaft, a power wheel and operating chains therefor, a bearing hood, a pivot carried by said hood, side bars connecting the bucket sections with the pivot at the bearing hood, a plurality of suspender bars depending from the pivot and carrying the operating chains, and means for preserving the normal vertical alignment of the side bars and the suspender bars, such means including a plurality of spacing lugs at the hooded bearing.

In testimony whereof, I have hereunto signed my name in the presence of two witnesses.

HERBERT S. ATKINSON.
